United States Patent

Des. 234,399
Patented Feb. 25, 1975

234,399

RESTRICTOR VALVE

Julian S. Taylor, 8300 SW. 8,
Oklahoma City, Okla. 73108

Filed Nov. 6, 1972, Ser. No. 304,152

Term of patent 14 years

Int. Cl. D23—01

U.S. Cl. D23—19

FIG. 2

FIG. 1

FIG. 3

FIG. 4

FIG. 5

FIG. 1 is a perspective view of a restrictor valve showing my new design;

FIG. 2 is a top plan view thereof;

FIG. 3 is a side elevational view thereof;

FIG. 4 is an elevational view taken from the end opposite that shown in FIG. 1; and

FIG. 5 is a bottom plan view thereof.

The broken line showing of indicia in FIGS. 1, 2, 3 and 5 is for purposes of illustration only.

I claim:

The ornamental design for a restrictor valve, substantially as shown and described.
